UNITED STATES PATENT OFFICE

149,869

DESIGN FOR A BOWLING BALL CASE

Myron L. Haney, Evanston, Ill.

Application November 20, 1946, Serial No. 134,944

Term of patent 3½ years

(Cl. D34—5)

To all whom it may concern:

Be it known that I, Myron L. Haney, a citizen of the United States, residing at Evanston, in the county of Cook and State of Illinois, have invented a new, original, and ornamental Design for Bowling Ball case, of which the following is a specification, reference being had to the accompanying drawing, forming part thereof.

In the drawing:

Fig. 1 is an end elevation of a bowling ball case embodying my new design;

Fig. 2 is a side elevation thereof;

Fig. 3 is a top plan view thereof;

Fig. 4 is a bottom view thereof.

I claim:

The ornamental design for a bowling ball case, substantially as shown.

MYRON L. HANEY.
